UNITED STATES PATENT OFFICE.

MARK K. BOWMAN, OF MONTCLAIR, NEW JERSEY.

DESIGN FOR A DOOR FOR FEED-WATER HEATERS AND SIMILAR APPARATUS.

No. 38,082.

Specification for Design.

Patented June 12, 1906.

Application filed March 29, 1906. Serial No. 308,794. Term of patent 7 years.

To all whom it may concern:

Be it known that I, MARK K. BOWMAN, a citizen of the United States, residing at Montclair, in the county of Essex and State of New Jersey, have invented a new, original, and ornamental Design for a Door for Feed-Water Heaters and Similar Apparatus, of which the following is a specification, reference being had to the accompanying drawing, forming a part thereof, and in which is

shown a face view of a door for feed-water heaters bearing and incorporating my design.

I claim—

The ornamental design for a door for feed-water heaters and similar apparatus, as shown.

MARK K. BOWMAN.
